UNITED STATES PATENT OFFICE.

CHARLES C. HANSEN, OF EASTON, PENNSYLVANIA, ASSIGNOR TO INGERSOLL-RAND COMPANY, OF NEW YORK, N. Y., A CORPORATION OF NEW JERSEY.

SECTIONAL BIT OR CUTTER.

No. 887,325.

Specification of Letters Patent.

Patented May 12, 1908.

Application filed June 18, 1906. Serial No. 322,183.

To all whom it may concern:

Be it known that I, CHARLES C. HANSEN, a citizen of the United States, and resident of Easton, in the county of Northampton 5 and State of Pennsylvania, have invented a new and useful Improvement in Sectional Bits or Cutters, of which the following is a specification.

My invention relates to a sectional bit or 10 cutter and particularly to a bit or cutter adapted for use on coal mining machines, with the object in view of providing a bit which may be constructed in an efficient and durable manner and which may be sharpened 15 by separating the prongs and manipulating one prong at a time.

A practical embodiment of my invention is represented in the accompanying drawings, in which

20 Figure 1 is a view in side elevation of a five-pronged bit in which the cutting edges are in radial lines with respect to the axis of the bit, Fig. 2 is a face view of the same, Fig. 3 is a side elevation of a five-pronged bit in 25 which one side of the prong is in a radial line from the longitudinal axis of the bit, the cutting edge being off-set from this radial line, Fig. 4 is a face view of the same, Fig. 5 is a view in detail showing one of the prongs of 30 the radial edged bit in side elevation, Fig. 6 is a top plan view of the same, Fig. 7 is a 35 face view of the same, Fig. 8 is a view in detail showing in side elevation one of the radial sided prongs, Fig. 9 is a plan view of the same, Fig. 10 is a face view of the same, Fig. 11 is a longitudinal section of the holder for 40 the radial edged prongs, Fig. 12 is an end view of the same, Fig. 13 is a longitudinal section of the holder for the radial sided 45 prongs, and Fig. 14 is an end view of the same.

While I have chosen for illustration a bit having five prongs, it is to be understood 50 that the bits may be constructed with a greater or lesser number of prongs at pleasure, the shanks of the prongs being so formed as to complete that part of a frustum of a cone which one prong bears to the whole 55 number of prongs, *i. e.*, if the number of prongs be five, then the shank of each will complete one-fifth of a frustum of a cone and its sides will diverge at an angle of 72°. If four prongs were employed, the shank of each would complete one-fourth of a frustum of a cone and the sides of its shank would

diverge at an angle of 90°. If six prongs were used, the shank of each would complete one-sixth of a frustum of a cone and the sides would diverge at an angle of 60°.

Referring first to the form as illustrated in 60 Figs. 1, 2, 5, 6 and 7, where the cutting edge is in a radial line to the longitudinal axis of the cutter, each prong consists of a shank 1 from which projects the body 2 offset from or diverging from the shank and terminating in 65 a cutting edge 3, which lies in a radial line to the longitudinal axis of the cutter. The sides 4 and 5 of the prong in this five-pronged cutter shown, diverge at an angle of 72° from the inner edge 6 which edge, instead of being 70 made sharp, is cut away to form a blunt edge.

The opposite sides of the prong are provided the one with a projection 7 and the other with a recess 8 for the reception of 75 projection on an adjacent shank, the projection on the adjacent shank corresponding to the projection 7.

When assembled with a projection 7 in its recess 8 in an adjacent prong, the whole group is inserted with its shank within the 80 opening 9 in the holder 10, the opening 9 being tapered to correspond to the taper of the outer face 11 of the shank so as to produce a wedge-like group upon the group of prongs to hold them firmly in position under end 85 pressure.

The interlocking of the several prongs, the one with another, serves to prevent any liability of one of the prongs shooting out independently of its neighboring prongs in the 90 event one should work loose while the others remain tight.

In the form shown in Figs. 3, 4, 8, 9 and 10, the prong is given a lateral offset as well as a radial offset and its cutting edge is brought 95 out of radial alinement as clearly shown in Fig. 4. In this from the shank is denoted by 12; the body of the prong by 13; its cutting edge by 14; and the radial side by 15. The shanks 12 of this form are shown without interlocking projections and recesses, the frictional pressure exerted thereon by pressing them endwise into the tapered opening 16 in the holder 17 being relied upon to hold them securely in position while in operation. 100 105

What I claim is:—

1. A bit for use in coal mining comprising a plurality of sections terminating at one end in shanks and at the opposite end in cutting edges, the end portions of said shanks being 110

- arranged to form when in assembled adjustment a frustum of a cone and a tapered holder adapted to closely embrace the assembled shanks where they form the frustum of a cone and press the said shanks into closely assembled adjustment under working impact.
2. A bit for use in coal mining comprising a plurality of prong sections, the shanks of the prongs being arranged to laterally interlock the one with another and a holder for holding the prongs in assembled adjustment.
- 10 3. A bit for use in coal mining comprising

a plurality of prong sections, each section being provided on one side with a projection 15 and on the other side with a recess and means for holding the several prongs in closely assembled adjustment.

In testimony, that I claim the foregoing as my invention, I have signed my name in 20 presence of two witnesses, this fourteenth day of June 1906.

CHARLES C. HANSEN.
